CLAIM

We claim the ornamental design for a water bottle, as shown and described.

DESCRIPTION

FIG. 1 is a perspective view of a water bottle showing our new design;

FIG. 2 is a front view of the water bottle of FIG. 1;

FIG. 3 is a rear view of the water bottle of FIG. 1;

FIG. 4 is a right side elevational view of the water bottle of FIG. 1;

FIG. 5 is a left side elevational view of the water bottle of FIG. 1;

FIG. 6 is a top view of the water bottle of FIG. 1; and, FIG. 7 is a bottom view of the water bottle of FIG. 1.

The broken lines in the drawings depict portions of the water bottle that form no part of the claimed design.

1 Claim, 6 Drawing Sheets
